FILM HOLDER

Eric G. Forssell, Kenmore, N. Y., assignor to W. H. Miner, Inc., Chicago, Ill., a corporation of Delaware

Application January 12, 1945, Serial No. 572,561

4 Claims. (Cl. 250—68)

This invention relates to improvements in film holders employed in X-ray photographing steel castings, and more particularly film holders for use in connection with castings in the form of tubular casings.

One object of the invention is to provide a film holder comprising inner and outer, tubular shells between which the film is held, and front and rear removable caps closing the front and rear ends of the shells, wherein the front and rear caps are clamped together by readily removable retaining means, thereby greatly facilitating loading of the film holder.

Other objects of the invention will more clearly appear from the description and claims herein-after following.

In the drawing forming a part of this specification, Figure 1 is a longitudinal, vertical sectional view of my improved film holder. Figure 2 is a front elevational view of Figure 1, looking from left to right in said figure. Figure 3 is a transverse, vertical sectional view, corresponding substantially to the line 3—3 of Figure 1. Figure 4 is a side elevational view of the locking head end of one of the retaining elements of my improved film holder.

As shown in the drawing, my improved film holder comprises broadly an inner tubular shell A; an outer tubular shell B; a front cap C; a rear cap D; and a pair of retaining elements E—E.

The shells A and B are of the same design, each being in the form of an elongated, cylindrical, tubular member. The inner shell fits within the outer shell with sufficient space therebetween to accommodate a single thickness of sensitized photographic film 10. The shells A and B are preferably made of fiber or any other similar material.

The caps C and D are of the same design. Each cap is in the form of a relatively thick ring or collar having an inwardly directed, outer, annular flange 11, a slightly inclined inner, annular wall 12, and a connecting transverse section 13, joining the flange 11 and the wall 12. The flange 11 and the wall 12 define an outwardly flaring slot 14 which forms an annular seat adapted to receive the corresponding ends of the shells A and B. As clearly shown in Figure 1, the wall 12 projects inwardly beyond the flange 11 and is provided at its inner end with a laterally inwardly projecting, annular wall portion 15, which terminates in an annular flange 16, which extends outwardly and defines the circular opening of the ring. Each ringlike cap C and D is provided with a pair of diametrically opposite slots 17—17 which

open inwardly of the ring and extend through the flange 16 and the wall 15 thereof. The slots 17—17 and 17—17 of the two rings are adapted to accommodate the rod or shank portions of the retaining elements E—E.

The retaining elements E—E serve to clamp the parts together, connecting the ringlike caps C and D. Each element E comprises an elongated shank portion in the form of a rod of cylindrical, 10 transverse cross section, headed at its rear end, as indicated by 18. The head 16 is similar to a round bolt head and is adapted to shoulder on the wall 15 of the rear cap D at opposite sides of the corresponding slot 17 thereof. At the forward 15 end, the shank of each element E is provided with a locking lug 19, which is in the form of a flat, L-shaped, platelike section projecting laterally from opposite sides of the rod or shank, thereby presenting rearwardly facing abutment shoulders 20—20. The shoulders 20—20 are adapted to bear on the wall 15 of the front cap C at opposite sides of the corresponding slot 17 thereof.

In loading the film holder, the sensitized photographic film is placed inside the shell B. The 25 shell A is then placed within the sensitized film and the outer shell B and the front and rear heads are applied, the flanges 11—11 being engaged over the corresponding ends of the outer shell B and the inner walls 12—12 forced into the 30 opening of the inner shell A at the front and rear ends thereof. The locking members E—E are next applied by passing the rodlike shank portions thereof in lateral direction into the slots 17—17 and 17—17 of the front and rear caps C and D 35 with the locking lugs extending edgewise so as to pass freely through the slot portions in the flange 16 of the front cap. Each locking element is then pulled forwardly to engage the head 18 thereof against the wall 15 of the cap D. Each rod is 40 then rotated through an angle of approximately 90 degrees by means of the lug 19 thereof to bring the locking shoulders 20—20 into overhanging locking relation with the wall 15 at opposite sides of the slot 17. The retaining elements when thus 45 locked clamp the caps C and D together, tightly wedging the opposite ends of the shells A and B into the flaring seats 14—14 of the caps.

I claim:

50 1. In a film holder, the combination with inner and outer tubular shells between which the film is adapted to be held: of front and rear caps closing the ends of said tubular shells; and a retaining element for clamping said caps together, comprising an elongated member having a head at one end and a locking lug at the

other end, said head and lug having shouldered engagement with said caps respectively.

2. In a film holder, the combination with inner and outer tubular shells between which the film is adapted to be held; of front and rear locking rings having seats within which the corresponding ends of said inner and outer shells are engaged; and a pair of locking elements connecting said caps and clamping the same together, each of said locking elements having a head at one end in shouldered engagement with one of said caps and a locking lug at the other end in shouldered engagement with the other cap.

3. In a film holder, the combination with inner and outer tubular shells between which the film is adapted to be held; of front and rear locking rings having seats within which the corresponding ends of said inner and outer shells are engaged; radial slots in each of said rings communicating with the openings of said rings, the slots of said front and rear caps being in longitudinal alignment; and a pair of elongated locking elements connecting said caps and clamping the same together, each element comprising an elongated shank portion accommodated in the corresponding slots of said caps, a head at the rear end of said shank in shouldered engagement with the rear caps, and a flat platelike locking

lug at the other end of said shank extending beyond opposite sides of the same and shouldered against the front cap at opposite sides of the corresponding slot.

5. 4. In a film holder, the combination with inner and outer tubular shells between which the film is adapted to be held; of front and rear locking rings having seats within which the corresponding ends of said inner and outer shells are engaged; radial slots in each of said rings communicating with the openings of said rings, the slots of said front and rear caps being in longitudinal alignment; and a pair of elongated locking elements connecting said caps and clamping the same together, each element comprising an elongated shank portion accommodated in the corresponding slots of said caps, a head at the rear end of said shank in shouldered engagement with the rear caps, and an L-shaped, flat, platelike locking lug adapted to pass edgewise through the corresponding slot of said front cap, said platelike lug projecting beyond opposite sides of said shank and being brought into shouldered engagement with said cap at opposite sides of the slot thereof when said locking element is rotated through an angle of 90 degrees.

ERIC G. FORSELL.
